UNITED STATES PATENT OFFICE.

JOSEPH F. JOY, OF FRANKLIN, PENNSYLVANIA, ASSIGNOR, BY MESNE ASSIGNMENTS, TO JOY MANUFACTURING COMPANY, OF FRANKLIN, PENNSYLVANIA, A CORPORATION OF DELAWARE.

LOADING MACHINE.

Application filed January 24, 1924. Serial No. 688,184.

The present invention relates to certain new and useful improvements in loading machines of the type shown and described in my United States Letters Patent No. 5 1,306,064 granted June 10, 1919, wherein means is provided to gather the coal from the floor of a mine and transfer it to conveniently placed cars for transportation from the mine.

10 In the mining of coal it is customary to undercut the face of the vein to a depth substantially equal to the width of the vein, after which the coal is blasted so as to break a large quantity of the coal from its 15 natural bed and to leave a great quantity of the coal standing in a shattered semi-solid state. I am aware that machines have been proposed having inclined conveyors with gathering mechanism at the lower forward ends thereof whereby the loose coal is gathered on to the conveyor and then transferred by means of the conveyor to conveniently placed cars positioned at the rear end of the conveyor. Various mechanical contrivances such as machine picks and the like, as well as miners working with picks, have been utilized for breaking down the standing shattered coal into the path of the gathering mechanism, involving considerable 25 expensive machinery or entailing labor of the most arduous character.

It is the primary object of the present invention to provide a machine of the class described embodying a gathering mechanism characterized by its capability of not only moving the loose coal on to the conveyor, but also capable of penetrating and jarring the standing shattered coal so as to break the same down into lumps of desirable sizes and then convey the same onto the conveyor.

Briefly stated, the gathering mechanism is very similar in character to that set forth in my above mentioned patent, but embodies 45 more efficient gathering arms for the operation of penetrating and breaking down the standing shattered coal and employs a radically different form of mechanism for moving the gathering arms in the substantially 50 reniform orbital paths.

These and other objects will appear in the following specification, reference being had to the accompanying drawings, in which—

Figure 1 is a side elevational view of a

loading machine embodying a gathering mechanism constructed in accordance with the present invention,

Figure 2 is a top plan view, partly broken away, of the machine shown in Figure 1,

Figure 3 is an enlarged transverse sectional view taken substantially on line 3—3 of Figure 1, with parts broken away and removed, and

Figure 4 is an enlarged fragmentary sectional view taken substantially on line 4—4 of Figure 2,

Fig. 5 is a detail indicating the area swept over by one of the gathering arms.

Like reference numerals indicate corresponding parts throughout the several views.

Referring more in detail to the drawings, the machine may embody any suitable form of portable truck —5— upon which the conveyor and the rest of the mechanism is mounted so that the machine may be readily transported from place to place in the mine. As shown, this truck is provided with axles —6— having wheels —7— adapted to travel along the rails —8— of the mine tracks.

Mounted upon the truck —5— in any preferred or desired manner, is a longitudinally arranged conveyor —9—, preferably of the well-known chain and scraper type and embodying a forward inclined portion which extends to a point in close proximity to the mine floor, and a rear substantially horizontal portion which discharges at a point above the pit car in the usual manner. As the particular mounting of the conveyor does not form any part of the present invention the same is not shown or described in detail, but, as in the construction of my above mentioned patent, suitable means should be provided as at —10— for raising and lowering the forward end of the conveyor so as to permit ready moving of the machine from place to place when not in use and to bring the gathering mechanism into close proximity to the floor during its operation.

The conveyor embodies the usual parallel chains —11— which travel above and below a suitable partition —12— and which are connected at suitable intervals by means of transverse scraper bars —13—, the chains passing around suitable sprockets provided on a head shaft —14—. One end of the head shaft —14— may be provided with a

sprocket wheel —15— suitably driven by means of a chain gearing —16— with the motor —17— mounted on the truck —5—. Said chain —11— together with the bars 5 —13— actuated thereby is termed the conveyor flight.

At the lower forward end of the conveyor —9— there is provided a gathering head which embodies a hollow shoe or apron 10 —18— which is adapted to rest and slide upon the floor of the mine and which is of a width substantially greater than the width of the conveyor flight and its carrying structure and embodies the extending side 15 portions disposed at opposite sides of the lower end of the conveyor and a forward portion disposed in front of the latter.

The side portions of the shoe —18— are provided with longitudinally arranged parallel elongated slots —19— in which are slidably and pivotally mounted the depending pins —20— of castings —21— forming part of the gathering arms. Each gathering arm additionally includes a finger member 25 —22— of pick blade formation which has its rear end pivotally mounted upon a horizontal axis as at —23— for vertical swinging movement within a socket —24— provided in the casting —21—. Each finger 30 —22— is preferably provided with a plurality of upwardly projecting spikes —25— adapted to assist in breaking up and dislodging the standing shattered coal. At a point directly above the pin —20—, the casting —21— is provided with an upstanding pin —26—, and a further upstanding pin —27— is also provided on the casting —21— outwardly of the pin —26— substantially in alinement with the finger 35 —22—, for a purpose which will presently become apparent. For the purpose of imparting differentially-reciprocating movements to said arms through said pins —26— and —27—, that is to say, a slidewise movement 40 through the pin —26— and a to-and-fro movement through the pin —27— the following mechanism is provided:

A shaft —28— is suitably mounted in bearings beneath the bottom of the conveyor —9— at a point rearwardly of the gathering head, and a relatively large spur gear —29— is secured upon each end of this shaft adjacent the sides of the conveyor as will be seen from an inspection 55 of Figures 1, 2, and 3. The shaft is driven by means of a suitable sprocket gearing —30— from the motor —17—, and each gear —29— meshes with an idler pinion —31— suitably mounted upon stub shafts 60 carried by the sides of the conveyor forwardly of the gears —29—. Arranged forwardly of and meshing with the pinions —31— are further spur gears —32— similar to the gears —29—, and these gears 65 —32— are also carried by stub shafts

mounted on the sides of the conveyor. Each of the gears —29— is provided with a laterally projecting crank pin —33— operatively connected to the pin —27— of the casting —21— at the adjacent side of the machine by means of a link —34— embodying a vertically pivoted end member —35— having one end pivoted on the pin —27— for horizontal swinging movement, and an end member —36— to which the intermediate member of the link is pivoted for relative horizontal swinging movement as at —37—, the member —36— being pivoted for vertical movement on the crank pin —33—. In other words, the links —34— 70 operatively connect the gathering arms with the crank gears —29— and the pivotal connections at the ends of the links make or form substantially universal joints at these points for allowing the relative angular movement of the parts in both vertical and horizontal directions which take place when the gears —29— are rotated for swinging the gathering arms about the pins —20— when traveling the arcuate portions of the paths —38— traveled by the tips of said fingers —22—.

The gears —32— are provided with outwardly projecting crank pins —39— operatively connected with the adjacent pins —26— of the gathering arms by means of links —40— which are jointed at the ends and pivoted to the pins —39— and —26— in substantially the same manner as described with respect to the links —34—. As shown in Figure 1 the gears —32— are disposed and maintain a position one quarter of a turn in advance of the gears —29— so that, for instance, when the pins —33— are disposed in a horizontal plane with the axes of the gears —29— and rearwardly of the shaft —28—, the pins —39— will be in a vertical plane with the axes of the gears —32—.

In operation, the motor —17— is placed into operation for driving the conveyor and for continuously rotating the gears —29— and —32— in the direction indicated by the arrows in Figure 1. Through the pivotally and longitudinally sliding mounting of the gathering arms and the crank and link mechanism above described, the gathering fingers are caused to describe substantially reniform orbits as indicated by broken lines 38 in Figure 2, it being noted that the cranks at one side of the machine are so related to those of the other side thereof that the operation of the fingers is alternate so that one is in the act of penetrating the coal at one side of the apron while the other is in the act of moving some of the coal on to the conveyor. The fingers, in traversing these orbits are moved first longitudinally forward to pass into and behind the mass of coal, then laterally and rear- 110

wardly to scrape the coal along the inclined plane formed by the upper wall of the shoe —18— and on to the conveyor, after which they recede forwardly from the conveyor to avoid sweeping of the coal off of the latter and with a quick action to the point of beginning.

The two gathering arms work alternately and at each cycle of their movement they 10 sweep over a sector-shaped area immediately in front of the entry to conveyor, as indicated by the dotted area in Fig. 5, and maintain a substantially continuous movement of coal on to the conveyor to be carried by the scraper flights or bars —13— rearwardly into the pit car.

By an inspection of said Fig. 5 it will be noted that the inner radius of said sector-shaped area is parallel to and coincides with 20 the lower line of the lower end of the conveyor flight —13—, whereby a clean and complete sweep and delivery of coal onto said conveyor is effected. The advantage of such action lies in the fact that no coal that 25 is actuated or gathered by the gathering mechanism is permitted to lie or remain upon the shoe —18—, where coal of a succeeding delivery will come into contact with it and cause an undue shattering of the coal 30 and a consequent wastage of same.

From the foregoing description it is believed that the construction and operation of the invention will be readily understood by those skilled in the art.

35 Minor changes may be made without departing from the spirit and scope of the invention as claimed.

It is noted that the form of the orbital paths traversed by the gathering arms can 40 be varied by proportioning the driving gears and link mechanisms differently. For instance, by spacing pins 26 and 27 closer together and changing the size of the crank gears, the paths would be larger and extend 45 outwardly toward the sides of the machine a greater distance.

What I claim is:

1. A loading machine of the class described 50 including an inclined conveyor, and a gathering mechanism including fingers inclined co-incidently to the inclination of said conveyor pivotally and longitudinally slidably mounted at opposite sides of the forward end of the conveyor, actuating means to slide and swing said fingers to cause the same to longitudinally penetrate material in advance of the conveyor and then move laterally and rearwardly to engage said material and move it on to the conveyor.

60 2. A loading machine of the class described including an inclined conveyor, and a gathering mechanism including fingers normally inclined in co-incidence with the inclination of said conveyor, pivotally and longitudinally slidably mounted at opposite

sides of the forward end of the conveyor, actuating means to slide and swing said fingers to cause the same to longitudinally penetrate material in advance of the conveyor and then move laterally and rearwardly to engage said material and move it on to the conveyor, said actuating means embodying crank and link mechanism operatively connected to the fingers.

3. A loading machine of the class de- 75 scribed including an inclined conveyor, a gathering mechanism for said conveyor comprising fingers normally arranged at an inclination coinciding with the inclination of said conveyor, and crank and link mechanism adapted and operable to cause said fingers to travel in non-circular, fixed orbital paths to engage material and move it onto the conveyor.

4. In a loading machine of the class de- 85 scribed, the combination with a conveyor flight of a downwardly-inclined carrying structure for said flight provided at the lower end thereof with similarly-inclined lateral projections, a gathering arm for said flight, a pivot slidably carried by one of said projections upon which said arm is mounted, means imparting slidewise movement to said pivot and to the arm carried thereby, actuating means connected to said arm at a point spaced laterally from said pivot arranged and operative to impart movement to said arm differentially to said slidewise movement, said slidewise and said differential movements co-operatively causing said gathering arm to sweep over a sector-shaped area, the inner radius of which coincides with the lower adjacent line of said flight, whereby all the material actuated by said arm is moved onto said flight.

5. A machine of the class described in- 100 cluding a conveyor having a shoe at the forward end thereof provided with longitudinally arranged slideways at opposite sides of the conveyor, gathering arms pivotally and slidably mounted upon the shoe and in said slideways, and means to slide and swing said gathering arms for causing the same to move in non-circular orbital paths to engage material and move it onto the conveyor.

6. In a loading machine of the class de- 110 scribed, the combination with a conveyor of a gathering mechanism comprising a finger arranged to sweep over a sector-shaped area adjacent and in front of the entry to said conveyor, the inner radius of said sector-shaped area being coincident with the lower, adjacent line of the conveyor flight so that 120 all the material being actuated by said finger is moved onto said conveyor, means causing said finger to execute said movement which includes a lineally-movable pivot upon which said finger is mounted, means causing said pivot to move lineally, and additional means 130

connected to said finger adjacent and eccentrically to the pivotal point thereof whereby said finger is caused to have movement other than that imparted to said pivot, and where-
5 by said finger is caused to execute the move-
ment aforesaid.

7. A machine of the class described in-
cluding an inclined conveyor having a shoe
at the forward lower end thereof, and a gath-
10 ering mechanism including a vertically
swingable, normally inclined finger pivotally
and slidably mounted adjacent each side of
said shoe, a pair of cranks mounted rear-
wardly of the shoe at each side of the con-
15 veyor, means to rotate said cranks, and links
operatively connected to the cranks and the
fingers for moving the latter in non-circular
orbital paths.

8. In a loading machine of the class de-
20 scribed, in combination, a conveyor organi-
zation which includes a downwardly-inclined
flight-carrying structure having at its lower
end laterally extending portions each pro-
25 vided in its upper face with a slot, a con-
veyer-flight operating in said carrying
structure, a gathering arm mounted upon
one of said laterally-extending portions
adapted to normally swing in a plane paral-
30 lel to the inclination of said carrying struc-
ture, a downwardly-extending pin carried
by said arm positioned and slidable within
one of said slots, an upwardly-extending pin
carried by said arm, an actuating device con-
35 nected to said upwardly-extending pin, an
additional actuating device for said arm con-
nected thereto in laterally-spaced relation to
said last-mentioned pin, and means impart-
ing differentially-reciprocative movements to
said actuating devices, and therethrough to

said arm whereby said arm is caused to 40
sweep over a sector-shaped area, the inner
radius of which is substantially co-incident
with the adjacent line of said conveyor flight.

9. In a loading machine of the class de-
scribed, a conveyor, a gathering mechanism 45
adapted to deliver coal to said conveyor in-
cluding a plurality of fingers and crank
operated links for moving the fingers in reni-
form paths which cross each other, each of
50 said fingers having a plurality of links at-
tached thereto at different points, operative
to impart relatively differing movements
thereto.

10. In a loading machine of the class de-
scribed, a conveyor organization comprising 55
a carrying structure having a vertically-
swinging gathering end provided with lat-
eral extensions, a conveyor flight carried by
said structure, a gathering arm for said con-
veyer having one end thereof mounted upon 60
one of said extensions for lineal sliding
movement of said end and a to-and-fro
swinging movement of the other end, said
other end of said arm being free and adapted
to have vertical swinging movement, means 65
imparting said slideable movement to said
arm, and means imparting said to-and-fro
swinging movement to said arm, whereby
said arm is caused to sweep over a sector-
shaped area, the inner radius of which is in 70
substantial co-incidence with the adjacent
lower line of said conveyor flight, so as to
cause all the material actuated by said gath-
ering arm to be moved onto said flight.

In testimony whereof I hereunto affix my 75
signature.

JOSEPH F. JOY.
